UNITED STATES PATENT OFFICE

124,223

DESIGN FOR A BOTTLE OPENER

Marshall S. Neal, South Pasadena, Calif.

Application March 18, 1940, Serial No. 91,018

Term of patent 3½ years

To all whom it may concern:

Be it known that I, Marshall S. Neal, a citizen of the United States, residing at South Pasadena, in the county of Los Angeles and State of California, have invented a new, original, and ornamental Design for a Bottle Opener, of which the following is a specification, reference being had to the accompanying drawing, forming a part thereof.

Fig. 1 is a face view of a bottle opener, showing my new design;

Fig. 2 is an end view, looking at the left; Fig. 3 is an end view, looking at the right end of Fig. 1; and

Fig. 4 is an edge view, taken looking down in Fig. 1.

I claim:

The ornamental design for a bottle opener, as shown.

MARSHALL S. NEAL.
